UNITED STATES PATENT OFFICE.

GEORGE LORIO, OF MOBERLY, LOUISIANA.

EXCAVATOR.

1,180,164.

Specification of Letters Patent. Patented Apr. 18, 1916.

Application filed June 4, 1914. Serial No. 842,997.

To all whom it may concern:

Be it known that I, GEORGE LORIO, a citizen of the United States, residing at Moberly, in the parish of St. Charles and State 5 of Louisiana, have invented a new and useful Excavator, of which the following is a specification.

This invention relates to excavators particularly designed for use in the construction 10 of levee foundations although it can be used wherever it is desired to dig a trench and to fill the trench with concrete.

One of the objects of the invention is to provide a machine having novel means for 15 digging a trench of uniform width and to any predetermined depth, the excavating elements being combined with means whereby any water which may accumulate in the formed trench will be bailed therefrom.

20 A further object is to combine with the excavating mechanism a structure whereby concrete may be fed into the trench at a point close to the excavating elements, means being provided for preventing the concrete 25 from flowing forwardly in the trench and onto the excavating elements.

With the foregoing and other objects in view which will appear as the description 30 proceeds, the invention resides in the combination and arrangement of parts and in the details of construction hereinafter described and claimed, it being understood that changes in the precise embodiment of the 35 invention herein disclosed, can be made within the scope of what is claimed, without departing from the spirit of the invention.

In the accompanying drawings the preferred form of the invention has been shown.

In said drawings:—Figure 1 is a plan 40 view of the machine, the upstanding frame thereon being shown in section. Fig. 2 is a view partly in side elevation and partly in section showing the machine in use, the section being taken on the line A—B Fig. 1. 45 Fig. 3 is a rear elevation. Fig. 4 is a vertical longitudinal section through one of the buckets of the excavator. Fig. 5 is an elevation showing a modified structure.

Referring to the figures by characters of 50 reference 1 designates the axles of the machine supported by wheels 2 and carrying longitudinal beams 3, 4 and 5. A platform 6 is supported by the beams 3 and 4 and carries a motor 7. The entire machine may be 55 propelled forward or backward in any suitable manner. For example and as shown in

the drawings, gears 8 may be secured to one pair of wheels 2, these gears meshing with drive gears 9 secured to the ends of a shaft 10 journaled on the beams 3 and 5. A 60 sprocket 11 can be loosely mounted on the shaft 10, this sprocket being provided with a conical clutch member 12 while another clutch member 13 may be feathered on the shaft. By means of a lever 14, the clutch 65 member 13 can be shifted into engagement with the clutch member 12, thereby to couple the sprocket 11 to shaft 10 so that, when the said sprocket is rotated, motion will be transmitted therefrom through shaft 10 and 70 gears 9 to gears 8 and wheels 2.

Sprocket 11 is adapted to receive motion, through a chain 15, from a sprocket 16 loosely mounted on a shaft 17 which is journaled on the beams 3 and 4. This sprocket 75 16 has a clutch member 18 adapted to be engaged by another clutch member 19 which is feathered on shaft 17. A lever 20 is provided whereby the clutch member 19 can be moved into and out of engagement with 80 clutch member 18, thus coupling or uncoupling the sprocket 16 relative to shaft 17. A sprocket 21 rotates with sprocket 16 and receives motion through a chain 22 from a sprocket 23 secured to a counter shaft 24 85 which is journaled above the platform 6 and receives motion, through a pulley 25, belt 26 and pulley 27 from the power shaft 28 of the motor 7.

Shaft 17 projects past the beam 4 and 90 into the space between said beam and the beam 5 and mounted to swing upon this shaft is a frame 29 one end portion of which projects into an upstanding frame 30 which is fixedly mounted on a cross beam 31 supported by the beams 3, 4 and 5. A windlass 32 is supported within the upper portion of frame 30 and is connected to the frame 29 by a cable 33 or the like. A sprocket 34 rotates with the windlass and is adapted to 100 receive motion through a chain 35 from a sprocket 36 carried by the lower portion of frame 30, this sprocket 36 being adapted to be rotated in any suitable manner, as by means of a crank handle 37. Thus it will 105 be seen that the frame 29 can be swung upwardly or downwardly about shaft 17 as a pivot.

Frame 29 overhangs the space between the 110 beams 4 and 5 and mounted on the shaft 17 38 and within the frame 29 is a sprocket 39 while another sprocket 39 is secured to a

shaft 40 which is journaled in frame 29 near its rear or free end. A hanger 41 is connected to the frame 29 and is adapted to be adjusted upwardly and downwardly, forwardly and rearwardly relative thereto, this hanger carrying an idler sprocket 42.

A brace 79 extends forwardly and upwardly from the hanger 41 and has its upper end slidably mounted within a guide 80 secured to the frame 29. An adjusting screw 81 is connected to the upper end of the brace 79 and engages an ear depending from the frame so that, by rotating this screw 81, the brace 79 can be shifted forwardly or rearwardly relative to the frame 29, thus to shift the sprocket 42 and loosen or tighten an endless chain 43 which is mounted on the sprocket 42 and on the sprockets 38 and 39. This endless chain carries excavating buckets and bailing devices. The idler sprocket 42 is normally under and in vertical alignment with the sprocket 39 so that the endless chain 43 is thus provided with a substantially vertical rear flight as shown.

Each excavating bucket is made up of a front wall 44 from the sides of which extend rearwardly projecting side walls 45, each of which has a series of saw teeth 46 along the lower edge thereof, the width of each side 45 increasing toward the rear end thereof. Each bucket is connected to one link of the chain 43 by a finger 47 or the like cast integral with or secured to said link and which is held to the front wall 44 by rivets or the like. Each bucket extends under two or more links of the chain and the sides 45 of the bucket are connected at their upper longitudinal edges by a cross strip 48 adapted to bear upwardly against the chain 43.

Depending from one of the links of the chain and between the rear end portions of the sides of the bucket is a finger 49 to which is secured a scraping blade 50 adapted to fit snugly between the sides 45 of the bucket.

Obviously any desired number of buckets may be used and these buckets can be spaced any desired intervals.

For the purpose of cleaning the buckets as they pass the front sprocket 38, a scraper 83 is pivotally mounted upon the frame 29 and extends to a point where it will be slidably engaged by the side walls of each bucket, this scraper being held yieldingly in active position by oppositely extending springs 84 extending from an arm 85 formed on or secured to the scraper 83.

Pivottally connected to the frame 29 near the shaft 17 is a guide trough 51 adapted to bear downwardly at its rear edge upon the surface of the ground and so proportioned as to receive the buckets successively as they are moved forwardly and upwardly in the manner hereinafter described. This guide

trough has its lower end located close to one side of a transversely extending trough 52 supported by the beams 4 and 5 and within which is arranged a conveyer worm 53. This trough 52 can be of any length desired and a sprocket 54 is preferably secured to one end of the shaft of the worm and is adapted to receive motion, through a chain 55 from a sprocket 56 secured to the shaft 17.

Interposed between every two buckets on the chain 43 is a finger 57 to which is secured a bailing blade 58 so proportioned as to extend throughout the width and down to the bottom of the trench cut by the buckets. These blades can be of metal, leather or any other suitable material.

A sprocket 59 is secured to shaft 40 and is engaged by an endless chain 60 which also engages a sprocket 61 secured to the shaft 17. Consequently the two shafts 17 and 40 are caused to rotate in unison.

A concrete mixer 62 is preferably mounted on the platform 6, the same being of any desired construction and being driven by a chain 63 engaging a sprocket 64 on the shaft 28 and a sprocket 65 on the actuating shaft 66 of the mixer. The outlet spout 67 of the mixer discharges into a boot 68 which is secured to a vertically adjustable standard 86 suspended between the beams 4 and 5 adjacent the rear ends thereof, said boot being held directly in line with and close to the depending portion of the chain 43. This boot has a depending front wall 69 from which hangs an apron 70 formed of leather or other suitable flexible material, and which apron is adapted to contact with the bottom of the trench formed by the excavating buckets and to extend throughout the width of the trench. Consequently any liquid or semi-liquid material deposited in the trench back of the apron 70 will be prevented from flowing forwardly into that portion of the trench in front of the boot.

The boot is provided with side walls 87 designed to extend into the formed trench so as to prevent the walls of the trench from caving in, and a roller 88 can be secured to the lower end of the standard 86 so as to travel along the bottom of the trench.

It will be understood that the machine can be propelled forward at any desired speed and under the control of the clutches 12-13. The conveyer worm 53 will be operated continuously while the clutch members 18-19 are in engagement with each other and the same will likewise be true of the endless chain 43. Frame 29 can be elevated at its rear end by means of the cable 33, thus to bring the front lower flight of the chain into a substantially horizontal position at the beginning of the cut. During the operation of the excavator, the frame 29 can be gradually lowered as the depth of the cut increases.

As the chain 43 is operated by the mechanism hereinbefore described, the teeth 46 upon the sides of the buckets will cut into the soil and, as the scraping blades 50 pass under the idler sprocket 42, they will be moved downwardly into position between the rear ends of the sides 45, thus closing the space between said sides and causing the dirt which has been received between the 10 sides of the bucket, to be scraped upwardly into the guide trough 51 from which it will be directed to the trough 52 and then conveyed laterally to the point of discharge. While the bucket is above the trough 52 it passes around the sprocket 38, the toothed sides 45 of the bucket swinging outwardly from the scraping blade 50 so that removal of the contents of the bucket is thus insured. Should any water accumulate within the 20 trench produced in the manner herein described, the blades 58, which extend down to the bottom of the trench and throughout the width thereof, will serve as bailing elements, forcing the water upwardly along 25 the incline at the front end of the trench and onto the surface of the ground. Thus the trench will be kept practically clear of water until it has been filled with concrete.

For the purpose of filling the trench, the 30 concrete is properly mixed within the mixer 65 and discharged into the boot 68. As before pointed out, the apron 70 extends to the bottom and throughout the width of the trench. Consequently, when the concrete is 35 discharged into the trench, it cannot flow forward ahead of the boot and where it is likely to come into contact with the excavating elements.

It will be seen that by utilizing a machine 40 such as herein described, a trench can be cut and filled with cement in practically one operation, the trench being of uniform width and of any desired depth and forming the mold in which the concrete foundation is 45 built in the manner set forth.

A machine of this type has been found 50 particularly desirable in constructing the foundations of levees but it is to be understood that the same can also be used in the construction of foundations for large buildings, and for like purposes.

Where the buckets and chains are of considerable weight and the soil is comparatively soft, the idler sprocket 42 can be 55 pended with in which event the buckets will, by their own weight, dig into the soil. Furthermore, instead of utilizing buckets such as have been described, saws can be

used, these saws 71 being driven by a shaft 72 which receives motion, through a chain 60 73, from a sprocket 74 mounted on a shaft 75 which corresponds with the shaft 17. The shaft 72 is preferably mounted on a frame 76 mounted to swing about the shaft 75 and which can be adjusted upwardly 65 and downwardly by means of a cable 77 in the same manner as heretofore described with reference to the frame 29. The saws will cut into the soil and throw it upwardly 70 onto inclined blades 78 which extend between the saws and serve to direct the loosened and elevated soil into a trough such as shown at 52 in Fig. 2.

It is to be understood that if desired, the machine can be propelled forward in any suitable manner, as by means of a block and tackle and, if preferred, the trench formed by the machine can be left open so as to be used for laying pipes or for drainage purposes.

The toothed side walls 45 will operate to cut through any material in the path thereof and the blades 50 constitute sharp chisels of steel designed to cut through the material cut by the teeth 46.

What is claimed is:—

1. A machine of the class described, comprising a movably supported frame, an endless chain movably carried thereby and having rear and lower flights diverging upwardly, means carried by the chain for sawing parallel cuts in the soil and obstructions embedded therein, and means carried by the chain for scraping upwardly above the level of the ground the soil loosened between the saw cuts.

2. A machine of the class described, including a movably supported frame, an endless chain depending therefrom and having upwardly diverging rear and lower flights, means carried by the chain for sawing parallel cuts in the soil and through obstructions embedded in the soil, means carried by the chain for scraping loosened soil from between the cuts and to points above the surface of the ground, and means adjacent the rear flight of the chain for constituting a partition extending throughout the width and depth of the trench.

In testimony that I claim the foregoing 110 as my own, I have hereto affixed my signature in the presence of two witnesses.

GEORGE LORIO.
